UNITED STATES PATENT OFFICE.

FRANK H. CALDWELL, OF CHATTANOOGA, TENNESSEE.

SINK.

No. 918,124.

Specification of Letters Patent. Patented April 13, 1909.

Application filed September 14, 1907. Serial No. 392,931.

To all whom it may concern:

Be it known that I, FRANK H. CALDWELL, a citizen of the United States, residing at Chattanooga, in the county of Hamilton and State of Tennessee, have invented a new and useful Improvement in Sinks, of which the following is a specification, reference being had to the accompanying drawing.

My improvement relates particularly to metallic or porcelain sinks having a main approximately horizontal recessed or basin portion and having an upright back rising from said horizontal portion and adapted to be applied flatwise against an upright wall.

The object of the improvement is to provide for such a sink a lateral extension adapted also to be applied to the wall to which the sink is applied and to serve as a "drain-board" for draining water from dishes and similar articles, resting upon said extension, into the sink, said extension or "drain-board" being manufactured as a single piece distinct from the sink proper, so that the sink proper may be used with or without said extension. And the extension is to be made in "right" and "left" forms, so that it may be applied to either or both sides of the sink proper. In some situations there is room for such an extension at only one side of the sink proper and in other situations there is room for such an extension at both sides of the sink proper. Thus the manufacture of only three pieces, a sink proper adapted for use without drain-board, a left hand drain-board and a right hand drain-board, will meet a variety of needs. The improvement is also applicable to corner sinks—sinks applied to the two upright walls in the corner of a room.

In the accompanying drawings, Figure 1 is a front perspective of a sink proper with a drain-board at each side; Fig. 2 is a similar view of the same sink with a drain-board applied only at the right hand side; Fig. 3 is a perspective of the left hand drain-board shown in Fig. 1; Fig. 4 is an upright section on the line 4—4 of Fig. 2; Fig. 5 is a front perspective of a corner sink and a drain-board; Fig. 6 is a front elevation, portions being broken away; Fig. 7 is a section on the line 7—7 of Fig. 6; Fig. 8 is a section on the line 8—8 of Fig. 4.

Referring to said drawings, A is the sink proper, B is a left hand drain-board, and C is a right hand drain-board. The sink, A, is of a form heretofore manufactured. It con-

sists of a horizontal, approximately rectangular basin, 1, and an upright back, 2, rising from the rear portion of the basin. In the said back are two holes, 3, 3, for applying faucets in the usual manner. As to its details of form, said sink may, obviously, be varied. In the particular form shown in the drawings, an apron, 4, extends around the front and ends of the basin and is curved inward around its upper edge and meets and unites with the outward-curved upper edge of the basin wall, said wall and said apron being integral. Thus the front and end edges, rims, or gunwales, 5, of the basin are rounded in cross-section. The back, 2, is bordered along the top and ends by a forward-directed rib, 6, which meets and unites with the rim, 5. The right and left hand ends of the back, 2, are approximately straight and upright.

The sink proper, as thus described, is, in itself, complete and extensively used. Another form of sink, extensively manufactured, consists of a single piece approximately twice as long as the sink above described, and comprising a depressed portion or basin and an inclined portion serving as a drain-board. And to meet all conditions, said large structure must be made in two forms, one with the drain-board portion at the right and the other with said portion at the left. The manufacture of this relatively large structure in either of these forms is troublesome and expensive. First the forming of the large body is difficult, and when failures occur the loss is relatively large, and subsequently the work of applying the coat of enamel is much more difficult than is the task of applying the enamel to relatively small pieces. Whether such sinks are made of porcelain or of metal, the manufacture of these large forms is difficult and accompanied with a relatively high ratio of loss through failures.

Turning now to the extension or drain-board, B, of Fig. 1, said extension is a single piece comprising as main elements the approximately horizontal flat portion, 7, and the upright back, 8. Said back has at its right an upright edge, 9, conforming to the adjacent upright edge, 10, of the back, 3, of the sink proper, the meeting edges of said two backs abutting in such manner as to form a close or substantially invisible joint, the back, 8, being approximately as thick as the back, 2, and lacking the rib, 6, along said edge so that the adjacent portion of the rib,

6, stands in relief with reference to the adjacent faces of both of said backs. The main portion, 7, of the extension, B, is slightly inclined toward the basin, 1, so that liquids falling upon the portion, 7, will flow toward and into said basin. And said portion, 7, is extended rightward beyond the back, 8, far enough to extend across the adjacent portion of the rim, 5, of the basin, 1, and curve 10 downward to form an apron, 11. From the lower portion of the edge, 9, of the back, 8, to the front lower edge of the apron, 11, a rim or wall, 13, rises from the portion, 7, and extends across the joint between the backs, 15 8 and 2, and around the adjacent portion of the rib, 6. Along the front and left hand edges of the portion, 7, is a raised rib, 14, and said rib projects a short distance rightward of the right hand edge of said portion, 20 7; and the lower portion of the part of the rib thus extended is provided with a recess, 15, adapted to receive the rim, 5. The drain-board, C, at the right of the sink proper, A, is a duplicate of the drain-board, 25 B, excepting that there is a reversal of parts from left to right.

The sink and the drain-boards may be secured to the wall in any suitable manner, as by means of ordinary brackets extending 30 beneath said sink and drain-boards or by means of any suitable hanging or securing plates or other devices located between the backs, 8 and 2, and the wall, the sink proper and the drain-board or boards being preferably supported independently of each other. In Figs. 6 and 7, a plate, 16, secured to the wall, has sockets, 17, above for the reception of lugs, 18, projecting downward from the upper portion of the back, 2, and ears, 19, 40 for receiving bolts, 20, extending through ears, 21, on the rear portion of the bottom of the basin. In Figs. 4 and 8, the same means are used for supporting the drain-board.

I claim as my invention:

45 1. The combination with a one-piece sink proper comprising a basin and a back as long as the basin, of a one-piece drain-board distinct from said sink proper and comprising a nearly horizontal main portion and a back 50 having an upright, transverse end face, said back abutting endwise against the back of the sink proper and said nearly horizontal portion extending beyond said back of the drain-board across the adjacent portion of the rim of said basin.

2. The combination with a one-piece sink proper comprising a basin and a back as long as the basin, of a one-piece drain-board distinct from said sink proper and comprising 60 a nearly horizontal main portion and a back having an upright, transverse end face, said back abutting endwise against the back of the sink proper and said horizontal portion extending beyond said back of the drain-board across the adjacent portion of the rim

of said basin and curving downward to form an apron.

3. The combination with a one-piece sink proper comprising a basin and a back as long as the basin, of a drain-board distinct from 70 said sink proper and comprising a nearly horizontal main portion and a back having an upright, transverse end face, said back abutting endwise against the adjacent upright edge of the back of the sink and said 75 nearly horizontal portion extending beyond said back of the drain-board across the adjacent portion of the rim of said basin, and a rim rising from said nearly horizontal portion and extending across the joint between 80 said backs.

4. The combination with a one-piece sink proper comprising a basin and a back as long as the basin, of a drain-board distinct from 85 said sink proper and comprising a nearly horizontal main portion and a back having an upright, transverse end face, said back abutting against the adjacent upright edge of the back of the sink proper and said nearly horizontal portion extending beyond said 90 back of the drain-board across the adjacent portion of the rim of said basin and curving downward to form an apron, and a rim rising from said nearly horizontal portion and extending across the joint between said backs. 95

5. The combination with a one-piece sink proper comprising a basin and a back as long as the basin, of a one-piece drain-board distinct from said sink proper and comprising a nearly horizontal main portion and a back 100 having an upright, transverse face and abutting endwise against the adjacent upright edge of the back of the sink proper and said nearly horizontal portion extending beyond said back of the drain-board across the adjacent portion of the rim of said basin and having a recess receiving the front rim of the 105 basin.

6. The combination with a one-piece sink proper comprising a basin and a back as long 110 as the basin, of a one-piece drain-board distinct from said sink proper and comprising a nearly horizontal main portion and a back having an upright, transverse end face, said back abutting endwise against the back of the 115 sink proper and said nearly horizontal portion extending beyond said back of the drain-board across the adjacent end portion of the rim of said basin and across the front portion of said rim.

7. The combination with a one-piece sink proper comprising a basin and a back as long as the basin, of a drain-board distinct from 120 said sink proper and comprising a nearly horizontal main portion and a back having an upright, transverse end face, said back abutting endwise against the back of the sink proper and said nearly horizontal portion extending beyond said back of the drain-board across the adjacent end portion of the rim of 125 130

said basin and across the front portion of said rim, and a rim rising from said nearly horizontal portion and extending across the joint between said backs.

- 5 8. The combination with a one-piece sink proper comprising a basin and a back as long as the basin, of a drain-board distinct from said sink proper and comprising a nearly horizontal main portion and a back having 10 an upright, transverse end face, said back abutting endwise against the back of the sink proper and said nearly horizontal portion extending beyond said back of the drain-board across the adjacent portion of the rim of said 15 basin, and means for supporting said sink proper and said drain-board.

9. The combination with a one-piece sink proper comprising a basin and a back as long as the basin, of a drain-board distinct from

said sink proper and comprising a nearly 20 horizontal portion and a back having an upright, transverse end face, said back abutting endwise against the back of the sink proper and said nearly horizontal portion extending beyond said back of the drain-board across 25 the adjacent portion of the rim of said basin, and means for supporting said sink proper and said drain-board independently of each other.

In testimony whereof I have signed my 30 name, in presence of two witnesses, this tenth day of September, in the year one thousand nine hundred and seven.

FRANK H. CALDWELL.
